UNITED STATES PATENT OFFICE.

WILLIAM E. HATHEWAY, OF BRIDGEPORT, CONNECTICUT.

GARMENT BUCKLE.

Application filed November 11, 1924. Serial No. 749,123.

My invention relates to garment buckles of the one-piece type, and it consists in certain details of construction to be more fully set forth in the following description of its general features and advantages.

Referring to the accompanying drawings wherein the same numerals and letters of reference indicate like parts throughout the several views:

10 Figure 1 represents the blank or first operation of buckle construction—

Figure 2 is a view of the completed buckle—

15 Figure 3 is a side elevation of the complete buckle—

Figure 4 is a plan view of the buckle and a section of webbing showing the initial step of installing or anchoring the webbing to the buckle—

20 Figure 5 is an enlarged side elevation of the buckle showing the method of anchoring the webbing thereto—

Figure 6 is an enlarged side elevation of the buckle showing a section of webbing anchored with its free end carried beneath the base—

Figure 7 is a plan view of the buckle and webbing as shown in Figure 6—

Figure 8 is an enlarged central sectional view of the assembled buckle and webbing on line 8—8 of Figure 9—

Figure 9 is a plan view of the assembled buckle and webbing, and broken view of the latter—

35 Figure 10 is an enlarged modified construction of the buckle showing the webbing clamping element located below the base, also a section of webbing secured thereto—

Figure 11 is a plan view of the buckle showing the webbing clamping element located in the base and in open position therewith—

Figure 12 is an edge view of the top rail of the buckle showing the arms of the head turned back, and

Fig. 13 is a section on line 13—13 of Fig. 11.

The single piece sheet metal blank shown in Figure 1 is shaped to form a base and head. The former is divided by the elongated opening 1 into the two parts 2 and 3, the part 2 to be hereinafter designated as the base, and the latter as the clamp. The head part of the buckle consists of the opening 4 parallel with the opening 1, arms 6,

and the rail 7 from which depend the teeth 5.

After the blank shown in Figure 1 is formed, the teeth 9, on the lower edge of the clamp 3, are first turned inward at right angles to the clamp and said clamp is then folded on the line a—a to overlie the base 2, as shown in Figure 5. The arms 6 are elevated at an obtuse angle to the upper surface of the base 2, and the teeth 5 are carried back and below the arms and the edge of the rail 7 is also given a downward curve to avoid forming an obstruction to parts of the clothing.

When the several parts of the buckle are 70 in the position shown in Figure 5, the end of the webbing 10 is inserted under the slightly raised clamp 3 and fully seated thereunder, as also shown in Figure 4. The purpose of the elongated opening 1 is to expose the extreme end of the webbing and thus show that it is fully seated under the clamp 3, which clamp is then firmly closed upon the webbing with its teeth 9 embedded therein, thus firmly anchoring the end of the 75 webbing to the buckle. The opening 1 thus prevents faulty seating of the end of the webbing by careless operatives, as such end must be fully exposed to view to insure proper seating.

When the end of the webbing is thus firmly anchored, its free end is first passed through the opening 4 of the head and carried back along the underside of the base 2, see arrows, Figures 6 and 7, thence, see Figures 8 and 9, returned over the clamp 3, and a second time passed through the opening 4 of the head and brought into engagement with the teeth 5. The sharp pointed ends 5^a of the teeth project toward the base of the 80 buckle and at approximately right angles to their main body for a secure and certain grip on the webbing. This is an essential feature in hose supporters for which this particular buckle is specially designed. These 85 curved teeth absolutely prevent slipping of the buckle under the usual backing and filling to which it is constantly subjected, which result could not be obtained were the teeth not thus curved.

In Figure 10 is shown a modified construction of the buckle, wherein the clamp, designated as 3*, occupies a reverse position from that shown in the other views. In this view it will be observed that the clamp over-

lies the underside of the base 2. The teeth 9^a will also occupy a reversed position as shown. In other respects, the rest of the buckle construction remains the same as shown in the other views. There is, however, a slight change in the manner of threading the webbing in this modified construction. It will be noted, Figure 8, as before mentioned, that after the end of the webbing is anchored, the free end is passed twice through the opening 4 of the head, while in the modified construction it only passes once through said opening.

In Figure 11, the clamp 11 is divided by the U-shaped opening 12, and is struck up from the base 2^a with the teeth 13 formed on its edge, which teeth are pierced from the openings 14 of the base. The head portion of this buckle construction is the same as shown in the other views, and the manner of threading the webbing is the same as shown in Figure 8. The clamp 11 is narrower than the opening 15, from which it is pierced, to avoid shearing the webbing when closing the clamp thereagainst.

If desired the arms 6 could be turned back as shown in Figure 12, to give a more finished appearance to the buckle.

Having thus described my invention what I claim is:—

1. A one piece sheet metal buckle comprising a base and a head disposed at an obtuse angle to each other, said base having integral therewith a webbing clamping member having teeth along its edge and extending at an angle to said base, and said head having an elongated opening bounded by side arms and a top rail, the latter having teeth along its edge and extending at an angle to the head.

2. A one piece sheet metal buckle comprising a base and head, said base having an elongated opening dividing the base into two parts, one of said parts folded to overlie the other part to form a clamp to anchor the end of a strip of webbing with the end of the webbing exposed in the elongated opening to insure its being fully seated under the clamp, said head having an elongated opening parallel with the base opening forming side arms projecting from the base with a top rail integral with the arms and having teeth depending therefrom to engage the webbing, said head elevated above the upper surface of the base and at an obtuse angle thereto with the teeth projecting below the arms.

3. A one piece buckle comprising a base and head, the base divided by an elongated opening, said base adapted to be folded on a line with said opening to overlie the remaining portion of the base for securing the end

of webbing thereto, the head having an elongated opening parallel with the former opening and comprising side arms and a top rail having teeth depending therefrom, said head elevated above the upper surface of the base and at an obtuse angle thereto with the teeth projecting below the arms and at an angle thereto.

4. A one piece buckle, comprising a base and head, said base having an elongated opening therein and folded on a line with said opening to form a clamp for securing the end of webbing between the clamp and base, the head having an elongated opening parallel with the opening in the base, said head comprising side arms and a top rail having teeth depending therefrom, said head elevated above the upper surface of the base and at an obtuse angle thereto with said teeth projecting below the top rail and arms of the head.

5. A one piece buckle comprising a base and head, the base divided by an elongated opening, said base adapted to be folded on a line with the opening to overlie the remaining portion of the base to form a clamp for the end of the webbing, the head having an elongated opening parallel with the opening in the base and comprising side arms and a top rail having teeth depending therefrom, said head elevated above the upper surface of the base and at an obtuse angle thereto, the teeth projecting below the arms with their points inturned toward the base.

6. A one piece buckle comprising a base and head, the base divided by an elongated opening, said base folded on a line with the opening to overlie the remaining portion of the base for securing the end of webbing, the head having an elongated opening parallel with the opening in the base and comprising side arms and a top rail having teeth depending therefrom, said head elevated above the upper surface of the base and at an obtuse angle thereto with the teeth projecting below the top rail and rearwardly of the opening in the head with their points inturned toward the base.

7. A one piece buckle comprising a base and head, said base having integral therewith a clamping member for the end of webbing, said head elevated above the base and at an obtuse angle thereto, said head having an elongated opening with teeth formed on its upper edge and depending rearwardly therefrom with their points inturned toward the base.

In testimony whereof I affix my signature.

WILLIAM E. HATHEWAY.
